UNITED STATES PATENT OFFICE.

SAMUEL HALL, OF EAST ORANGE, NEW JERSEY.

METHOD OF PRODUCING IMITATION PRESS-COPIED LETTERS.

SPECIFICATION forming part of Letters Patent No. 423,558, dated March 18, 1890.

Application filed April 13, 1889. Serial No. 307,170. (No specimens.)

To all whom it may concern:

Be it known that I, SAMUEL HALL, a citizen of the United States, and a resident of East Orange, in the county of Essex and State of New Jersey, have invented certain new and useful Improved Methods of Producing Imitation Press-Copied Letters, of which the following is a specification.

My invention relates to a new and useful method of producing circulars, circular letters, and similar printed matter, whereby they shall have the appearance of having been letter-press copied, thus giving them more consequence in the eyes of the person by whom they may be received and inducing him to read the same.

In practicing my method it will be apparent that the printed matter may be produced upon the original in such manner as preferred. The methods most favored by me are printing the same on an ordinary press in type-writer type or by a plate in imitation of handwriting.

I prefer that my process should be practiced by the employment of an endless and continuously-moving web of cloth, and in order that the ink taken off upon the cloth may be removed from it, so that the original printed matter may not be smutched or "overprinted" by impressions taken from the cloth, I prefer to practice my invention by employing an apparatus devised by me and shown in the accompanying drawings, in which—

Figure 1 illustrates a vertical section, and Fig. 2 illustrates a top view.

A is a frame supported on a base B.

C C' are two water-tight tanks.

D D' are bars or rollers placed in the tanks below the surface of the liquid therein, respectively, under which the web of cloth, hereinafter described, passes, thus securing the submersion of the web and causing it to move through the requisite quantity of the liquids to accomplish the objects sought.

E is a roller supported on a part of the frame A.

F F' F' F' are pairs of squeezing-rollers journaled in suitable supports G G', which are preferably supplied with adjusting-screws H H', whereby the rollers may be adjusted

toward and from each other for the purpose of regulating the dryness or moisture of the web in a manner now well understood in connection with clothes-wringers and the like devices. I I' are similar rollers journaled in the upper part of the frame A, also provided with an adjusting set-screw J, and one of them, preferably the lower, as shown, has a crank K attached to its journal. If desired, a pulley for the employment of power may be used instead of the crank.

L is a frame provided at its upper part with a roller M, and hinged or pivoted at the bottom at N to the base B, and having set-screws O threaded through a suitable part of the frame L, which bears against the frame A, as shown.

P is an endless web, of cloth or other suitable material, which passes over, under, and around the several rollers and between the compression or squeezing rollers, as shown, and the slack of this endless belt is taken up as it wears, or its tightness may be regulated by throwing the frame L outwardly from the frame A by means of the set-screw O. This will tighten the web.

The operation is as follows: The tank C' contains a solution of chloride of lime or other equivalent bleaching material. The tank C contains water, which may be treated chemically, if preferred, to more effectually remove or neutralize the bleaching solution. The crank K being turned, the endless web starts, coming wet from the tank C, and the printed sheets are passed in succession and face downward upon the wet surface of the web in between the rollers I' and I, and thus an imprint is taken on the web from the ink on the paper. The sheets may remain on the web until they drop off at the roller M. The web passes continuously under the bar or roller D', through the bleaching-liquid, where the ink is destroyed, and thence passes between the squeezing-rollers F F', which squeeze out the excess of the bleaching-liquid. Thence the web passes up over the bar or roller E, thence under the bar D and through the water in the tank C, where the bleaching-liquid is washed out from the web; thence between the squeezing-rollers F' F', which press out the excess

of water, and by means of which the dampness of the web for further press-copying the sheets can be regulated. The web then passes direct to the rollers I' and I. Thus the circuit 5 of the web is completed, it returning again for further use freed from the ink deposited by the sheets previously acted upon.

The rollers may be made of such material and may be shaped on their surface so as to 10 properly guide the web as may be deemed most desirable.

I do not herein claim the apparatus shown and described; but I do not abandon the same, since I intend to make that the subject 15 of an application for a patent to be filed by me before the allowance of this present application.

I claim—

1. The process described, consisting in first 20 printing the original sheets, then placing their printed surfaces in contact with a moist material and passing both together between compression-rollers, then removing the ink-

impression received by the moist material before it is again brought in contact with the 25 printed matter, substantially as and for the purposes set forth.

2. The process described, consisting in first printing the original sheets, then placing their printed surfaces in contact with a moist 30 material, then passing both together between compression-rollers, then passing the moist material through bleaching-liquor, then squeezing out the excess of bleaching-liquor, then passing the moist material through wa- 35 ter to wash out the bleaching-liquor, then pressing out the excess of water, substantially as set forth.

Signed at New York, in the county of New York and State of New York, this 8th day of April, A. D. 1889.

SAMUEL HALL.
